United States Rubber Company, New York, N.Y., a
corporation of New Jersey

Filed Feb. 24, 1965, Ser. No. 83,966

Term of patent 14 years

(Cl. D90—20)

Fig. 1

Fig. 2

Fig. 3

FIG. 1 is a perspective view of a tire embodying my new design, it being understood that the full line portion is repeated throughout the circumference of the tire, shown by means of broken lines;

FIG. 2 is an enlarged fragmentary plan view of the full line portion shown in FIG. 1; and

FIG. 3 is a sectional view taken substantially on the plane indicated by the line III—III in FIG. 2.

The dominant features of my design reside in those portions shown in full lines in the drawings.

I claim:

The ornamental design for a tire, substantially as shown and described.
